UNITED STATES PATENT OFFICE

94,666

DESIGN FOR A RADIOCABINET

Archie Dahl, Chicago, Ill.

Application December 17, 1934, Serial No. 54,446

Term of patent 3½ years

To all whom it may concern:

Be it known that I, Archie Dahl, a citizen of the United States, residing in Chicago, in the county of Cook and State of Illinois, have invented a new, original, and ornamental Design for Radio Cabinets, of which the following is a specification, reference being had to the accompanying drawing, forming a part thereof:

Fig. 1 is a perspective view of the cabinet in closed condition;

Fig. 2 is a perspective view from a different angle, with the cabinet in open condition.

I claim:

The ornamental design for a radio cabinet, as shown.

ARCHIE DAHL.
